DESIGN FOR A FOLDABLE CASE FOR EDIBLES OR OTHER ARTICLES

Jack E. Schenker, Chicago, Ill.

Application August 20, 1942, Serial No. 107,979

Term of patent 14 years

To all whom it may concern:

Be it known that I, Jack E. Schenker, a citizen of the United States, residing at Chicago, in the county of Cook and State of Illinois, have invented a new, original, and ornamental Design for a Foldable Case for Edibles or Other Articles, of which the following is a specification, reference being had to the accompanying drawing, forming a part thereof.

In the drawing:

Fig. 1 is a view of the outer cover side of a foldable case for edibles or other articles portraying my design in unfolded and flattened position;

Fig. 2 is a view of the reverse side of the case as shown in Fig. 1;

Fig. 3 is an edge view thereof;

Fig. 4 is a perspective view of the foldable case for edibles or other articles in folded position and adapted for carrying such edibles or other articles; and

Fig. 5 is another perspective view of the foldable case for edibles or other articles when refolded into transportable position when such case is devoid of its contents.

I claim:

The ornamental design for a foldable case for edibles or other articles, substantially as shown.

JACK E. SCHENKER.
